UNITED STATES PATENT OFFICE.

ALBERT HOSSFELD, OF LEWISTON, MINNESOTA, ASSIGNOR TO THE HOSSFELD MANUFACTURING CO., INC., OF LEWISTON, MINNESOTA, A CORPORATION OF MINNESOTA.

MANURE-LOADER.

1,345,088.

Specification of Letters Patent. Patented June 29, 1920.

Application filed February 9, 1918. Serial No. 216,161.

To all whom it may concern:

Be it known that I, ALBERT HOSSFELD, a citizen of the United States, residing at Lewiston, in the county of Winona and State of Minnesota, have invented certain new and useful Improvements in Manure-Loaders; and I do hereby declare the following to be a full, clear, and exact description of the invention, such as will enable others skilled in the art to which it appertains to make and use the same.

My invention provides what I have seen fit to designate as a manure loader, but which is, nevertheless, capable of a wide range of use for loading various other materials, such as sand, gravel, dirt, straw, and the like, into a wagon box or onto a rack.

Generally stated, the invention consists of the novel devices and combinations of devices hereinafter described and defined in the claims.

The present invention is in the nature of an improvement on or modification of the machine disclosed and claimed in my prior Patent No. 1,190,550, of date, June 11, 1916, entitled "Manure loader" and involves various important novel features of improvements which greatly improve the action of the machine.

In the present improved machine and in the prior machine, I employ one or more rotary forks or scoops in an arrangement wherein I utilize centrifugal force to hold the fork or scoop radially projected while it is picking up its load and provide a yielding device which will allow the fork or scoop to move radially toward the axis around which it rotates when it has been loaded, and its advance rotary movement retarded. The latter movement permits the loaded fork or scoop to pick itself up and pass over the pile upon which it is acting.

The chief novel features of the present invention are directed to the means for operating the fork or scoop on the plan above described. The term "scoop" will be herein used in a sense broad enough to include either a fork or shovel. For picking up manure, straw or the like, a fork will be used, while for picking up sand or dirt, for example, a scoop, shovel, or bucket will be employed.

For throwing the load from the fork or scoop, at the proper point in the upper movement thereof, I provide a so-called ejec-

tor and improved means for operating the same.

Preferably also, the loader is mounted on a carriage having wheels adapting it to move forward as the picking-up and loading operation advances; and preferably at least part of the wheels of this carriage are arranged to be driven by a motor that also serves to operate the machine in the loading action.

The invention also, as will hereinafter appear in the detailed description of the drawings, involves other important novel features.

In the drawings, like characters indicate like parts throughout the several views.

Referring to the drawings,

Figure 1 is a front elevation of the improved loader with the so-called hood thereof removed;

Fig. 2 is a right side elevation of the machine, some parts being removed;

Fig. 3 is a front elevation of the loading fork with its carrying arm, coöperating ejector and its actuating connections;

Fig. 4 is a side elevation of the parts shown in Fig. 3, looking at the same from the right toward the left, in respect to Fig. 3, and with some parts broken away and some parts sectioned;

Fig. 5 is a front elevation of the so-called stop link which limits the radial outward movement of the fork or scoop and involves a friction device for resisting initial inward movement thereof;

Fig. 6 is a side elevation of the parts shown in Fig. 5; and

Fig. 7 is a front elevation of the so-called combined shield and deflecting hood used in connection with the machine.

The various parts of the loader hereinabove described are all carried directly or indirectly from a truck or carriage involving a truck frame 8 on which is mounted a suitable motor, such as an internal combustion engine 9, the shaft 10 which is, as shown, provided with a driving pulley 11. So far as the broad features of this invention are concerned, the truck frame may be mounted on wheels, or otherwise, in various different ways, but preferably it is mounted on a multiplicity of wheels in the following novel arrangement.

At one side, the truck frame is provided with a pair of traction wheels 12 located,

- one ahead of the other and adapted to run on the ground; and on its opposite side, it is provided with a pair of relatively small flanged wheels 13 that are adapted to run 5 on a carriage rail 14 such as a 2x4 laid upon the ground. As shown, the wheels 13 are loosely journaled to yoke-like bearing brackets 15 rigidly secured to the adjacent side of the frame 8, as best shown in Fig. 1.
- 10 Located intermediate of the truck frame, is a transverse counter shaft 16 journaled in bearings 17 on said frame and provided at one end with a sprocket 18, and at its other end with a sprocket 19.
- 15 The hubs of the traction wheels 12 carry sprocket wheels 20 over which and the sprocket 18 runs an endless sprocket chain 21.
- 20 When the machine is at work, it will rest on the wheels 12 and 13 and the latter will preferably run on the rail 14. When, however, the machine, out of action, is to be moved from one distant place to another, it is preferably carried on two front wheels 25 22 and rear wheels 23. The rear wheels 23 are detachably journaled to suitable trunnion equipped brackets on the rear side end portions of the truck frame 8 while the wheels 22 are journaled to the axle of a sort 30 of lead truck 24 that is detachably connected to the front end of the frame 8 by a knob, ball or bar 25. Fig. 2 shows the machine supported from and carried by the said wheels 22 and 23.
- 35 Rigidly secured to and rising from the front portion of the truck frame 8 is a trussed superframe or standard 26 shown as made up of spaced A frames and suitable cross ties. Journaled in suitable bearings 40 on the uppermost portion of the superframe 26 is a driving shaft 27 which, at its rear end, carries a sprocket 28 and a pulley 29. A main driving belt 30 runs over the pulley 29, under the engine pulley 11 and against 45 a belt tightening pulley 31. This tightening pulley 31 is journaled on the crank end of a crank shaft 32 mounted in suitable bearings in the frame 26 and provided with a lever 33, by means of which it may be oscillated to move the said tightening pulley and put the belt 30 under driving strain at will.
- Extended transversely of the truck and 55 journaled in suitable bearings on the frame 26 and on a supplemental pedestal 26^a is a counter shaft 34 which, at one end, has a large grooved pulley 35 and near its other end has a small sprocket 36. A long endless sprocket chain 37 runs over the sprocket 36, 60 over sprockets 38 on the hubs of the small wheels 13, and over the sprocket 19 of the counter shaft 10. By the connections just described and those previously described, the traction wheels 12 and 13 will be simultaneously driven from the counter shaft 34.

The counter shaft 34 is arranged to be driven by a rope belt 39 that runs over the grooved pulley 35, over a grooved pulley 40 on the hub of the engine pulley 11 and over a pair of loose belt tightening pulleys 41. 70 These belt tightening pulleys 41 are journaled to a forked head 42 that is mounted to slide or move vertically on the upper portion of the adjacent side of the superframe 26 and is connected by a link 43 to a lever 44 pivoted to a suitable bearing on the frame 26. By manipulation of the lever 44 the pulleys 41 may be raised, at will, to tighten the belt 39 so that it will drive the shaft 34, and thereby, through the connections described, rotate the traction wheels of the truck and cause the machine to advance. Obviously, when the lever 44 is released, belt 39 will be given slack and will instantly cease its wheel driving action. 80

The scoop is carried by the free end of an arm that is pivoted to the crank end of a crank shaft, and this crank shaft is journaled in the free end of an arm-like supporting frame which, in turn, is pivotally 90 mounted for movement in either direction on the shaft 27 or on bearings surrounding said shaft and rigidly secured to the frame 26.

Describing these elements in the reverse 95 order from which they have just been enumerated, it will be noted that the said arm-like supporting frame is made up of a pair of rotary spaced metal bars 45, preferably trussed and suitably cross connected. The 100 crank shaft 46 is journaled in the free end of the said oscillatory frame 45 and the crank at its front end is formed by a radially projecting crank arm 46^a that has a back-turned crank pin portion 46^b (see particularly Figs. 1 and 2). The scoop carrying arm 47 (see Figs. 1, 3 and 4) is a bifurcated trussed structure and is pivotally 105 mounted on the crank pin 46^b of the crank shaft 46. The scoop shown is in the form 110 of a fork made up of a head 48 and tines 49, the said tines being in U-shape formation (see particularly Figs. 3 and 4); and the said head 48 is rigidly connected to the free end of the arm 47. 115

Normally, the fork-equipped end of the arm 47 is held in its maximum projection from the axis of the crank shaft 46 by an endwise contractible and extensible thrust link that includes in its structure a frictional detaining clamp the preferred arrangement of which parts will now be described in detail.

The body of the link is made up of a central bar 50 and outside clamping bars 51. 125 The inner end of the bar 50 is pivotally connected to a lug on the crank shaft 46, while the outer ends of the bars 51 are pivoted to the outer end of the arm 47. The extended end of the bar 50 is interlapped with the 130

- inner ends of the bars 51. That portion of the bar 50 that interlaps with the bars 51 is formed with frictional surfaces 50^a and 50^b and beyond the latter with a stop head 50^c.
- 5 The frictional portion 50^b is wider than the frictional portion 50^a and is united therewith by oblique cam surfaces, and the frictional portion 50^a is wider than the inwardly extended portion of said bar 50, and
- 10 is likewise united therewith by oblique cam surfaces. The small friction blocks 52 are interposed between the opposite faces of the friction surfaces 50^a and the inner ends of the bars 51 and similar friction blocks 53
- 15 are interposed between the friction surfaces 50^b and the said bars 51. The said shoes are clamped against the said coöperating frictional surfaces of the bar 51 by coiled springs 54 held in position by laterally spaced nut-equipped bolts 55 and coöperating metal clips 56. The said bolts 55 also guide the bars 50 and 51 for true endwise sliding movements. The numeral 57 indicates a buffer spring placed on the small inner end portion of the bar or link member 50. The function of the above described extensible link and frictional clamp will more fully appear in the description of the operation.
- 20 30 The head of the so-called load ejector is in the form of a flat plate 58 (see Figs. 1, 3 and 4) and is provided with perforations that freely pass the teeth of the fork 49 therethrough, so that normally, the said plate will lie flat against the head of the fork, as shown in said views. This head plate 58 is rigidly secured to the end of an ejector arm 59 which, at its inner end, is pivoted at 60 to brackets 61 on the arm 47.
- 25 35 40 Intermediately pivoted on the crank pin 46^b of the crank shaft 46 is an ejector operating bell crank 62 which, as shown, includes an oblique truss strap 62^a (see Figs. 1, 3, and 4). At its rear end, the bell crank 62 is provided with a roller 63, and at its front end, is connected to a link 64. This link 64, at its outer end, is pivotally connected to the intermediate portion of the ejector arm 59. The pivotal connection
- 45 50 55 60 65 between the link 64 and bell crank 62 is made adjustable by a nut-equipped bolt 65 that works in any one of a plurality of longitudinally spaced holes in said link. The purpose of this arrangement, as will herein-after appear, is to vary the amount of movement that will be given to the ejector head 58. A coiled spring 66 shown as attached to the ejector arm 59 at or near its pivot and the outer end of the bell crank 62, acting
- 70 75 80 85 90 95 100 through the link 64, yieldingly holds the ejector head or plate 58 normally against the fork head 48.
- Lying within the path of movement of the inner end of the bell crank 62 and positioned
- 105 110 115 120 125 130 for engagement with the roller 63 thereof,
- is an offset portion of a tripping abutment in the form of a trip arm 67 (see Figs. 1 and 4). This tripping abutment is in the form of a bell crank that is adjustable and shown as pivotally mounted on the crank shaft 46. The upper and lower arms of this bell crank 67 are shown as connected by a trussed strap 67^a. The lower arm of said bell crank 67 is connected to the outer end of an adjusting bar 68 which, at its inner end, has longitudinally spaced notches adapting it to be adjustably connected to a lug or detent 69 on one side of the frame 26.
- To counter balance the arm 47, fork 49, adjustable link and other parts carried therewith, I provide a counter-weighted arm 70 which, at its inner end, is pivoted on the crank shaft 46, and at its outer end has a quite heavy weight 71. The free end of the arm 70 is connected to the crank pin 46^b of the said crank shaft by an endwise resilient link made up of two telescopically movable or endwise sliding members 72 and 73 (see Fig. 1). The link member 72 is pivoted on the wrist pin 46^b while the outer end of the link member 73 is pivotally connected to the outer end of the arm 70. Opposing coiled springs 74 are placed on the rod member 72. These opposing coiled springs 74 react against an intermediate abutment 75 on the link member 73 and against collars or abutments 76 on the rod member 72. Hence, these coiled springs cushion the movement of the weighted arm 70 in both directions.
- Means are provided for supporting the oscillatory frame or supporting arm 45 in different vertical positions; and as shown, these means are as follows:
- The numeral 77 indicates an upright strut or post which, at its lower end, as shown, is anchored to the journal pin or bolt 13^a of one of the small traction wheels 13, and at its upper end is extended with clearance through and far upward beyond the outer end portion of the said frame or arm 45, and at its extreme upper end, has a sheave 78 (see Fig. 1). The numeral 79 indicates a chain or other form of cable which is attached at its outer end to the free end portion of the oscillatory frame or arm 45, is passed upward and over the sheave 78, thence downward and under a guide sheave 80 on a projection on arm 45, and thence is brought rearward and attached to a windless sleeve 81 journaled on the shaft 27 and provided with a hand wheel 82 by means of which said sleeve may be rotated to wind up or let out the chain 79, and thereby raise and lower the free end of the frame 45. Any well known means, such as the customary wheel and lock dog, may be used to lock the windless sleeve 81 against rotation to thereby hold the frame 45 set at any desired elevation.

The main crank shaft 46, at its rear end, is provided with a large sprocket 83 over which, and the sprocket 28 of the shaft 27, runs a sprocket chain 84, so that the said crank shaft will be driven from the said shaft 27. The numeral 85 indicates an idle sprocket carried by an arm 86 on the frame 45 and serves to take up the slack in the chain 84. Preferably, I provide also a compression coiled spring 87 which coöperates with other devices to yieldingly hold the arm 47 and its fork pressed forward in the direction of its rotation, which direction of rotation is indicated by the large arrow marked on Fig. 1. This spring 87 is placed on a rod 88, the inner end of which is pivotally connected to the main crank shaft 46, the outer end of which works freely through a passage in the arms 47. The fork will discharge its load while it is moving toward the left, in respect to Fig. 1 from its uppermost position toward a horizontal position. The numeral 89 (see particularly in Fig. 7 but noted also by dotted lines in Fig. 2) indicates a shield in the nature of a board set edgewise in a vertical plane and extended close to one side or along the line of discharge movement of the fork. This shield, as shown, is supported at one end by a braced link 90, and at its other end by a rod 91. The link 90 is pivotally connected to the shaft 46 or to the adjustable frame 45 adjacent to said shaft. The rod 91 moves telescopically in a tubular post 92 which, at its lower end (see Fig. 1) is pivoted to the front end of the truck frame 8. The numeral 93 (see Figs. 1 and 7) indicates an extension rod that is rigidly clamped to the upper end of the tubular post 92 and to the upper end of which is journaled a small windlass drum 94 formed on the hub of a hand wheel 95. A small chain or cable 96 is attached to the windlass drum 94 and the intermediate portion of the vertically adjustable rod 91, so that by rotation of the said windlass drum, the rod 91 may be vertically adjusted and the outer end portion of the shield 89 may be set at different elevations. Any suitable well known means may be provided for locking the windlass drum 94 and end wheel 95 against rotation. In Fig. 1, the numeral 97 indicates a lock dog pivoted to the rod 91 and with its free end engageable between the spokes of the said hand wheel for the above indicated purpose. At its inner end, the shield 89 is shown as provided with a laterally offset curved plate 98, and at its outer end, it is shown as provided with an approximately vertical stop plate 99 against which at least a part of the load will be thrown from the fork and then will drop into the wagon box or onto the rack. The numeral 100 indicates a board that projects laterally from the upper edge of the shield

89 and is connected to the upper portion of the deflecting board 99.

Operation.

The oscillatory supporting frame 45 will, of course, be so vertically adjusted that the fork will properly pick up its load from the ground or from a stack. Under rotation of the main crank shaft 46, the crank arm 46^a, fork arm 47 and link 50—51 will rotate together in triangular formation with the said link extended to its limit, as shown in Figs. 1, 5 and 6, and with the fork projected to its maximum radial distance from the axis of rotation.

When the fork reaches approximately the position shown by dotted lines in Fig. 1, it will be caused to pick up its load from the ground or from the stack, partly by the driving force of the driving connections described and partly by momentum. In the act of picking up the load the forward rotary speed of the fork will be greatly decreased, and if the resistance is considerable, it may be brought nearly to a stationary position. When the fork and its triangular support above noted revolve, the weighted arm 70—71 and resilient link 73 revolve therewith and the momentum of the said weighted arm will greatly assist in driving the fork into the stack, or in causing the same to pick up its load. The driving force of the weighted arms, as noted, will however, be cushioned by the springs 74 so that there will be no danger of breakage of any of the parts. When the motion of the fork in the load picking-up action is suddenly arrested, the outer spring 74 will be compressed and the reverse recoil from the arms will be taken by the inner of the said springs 74. The normal frictional clamping actions between the friction blocks 52 and 53 and the friction surfaces 50^a and 50^b, respectively, of the collapsible or contractible link 50—51 is such as to insure the proper entry of the fork or scoop into the stack or material to be picked up, but is not sufficient to resist the positive driving action and the hammer-like force delivered by the weighted arm 70—71, so that, as the fork approaches a position of rest in a position at a maximum distance from the axis of the crank shaft 46, the said frictional element of the link 50—51 will be overcome and the said link will shorten up and permit the fork and its arm 47 to swing on the wrist pin 40^b of the crank shaft 46, so that the fork is moved radially toward the said crank shaft. This has the effect of shortening the loaded fork beam so that it will pass over the engaged portion of the stack or pile from which the load was taken, and hence, will be free to continue its upward rotation which will immediately follow under the continued rotation of the crank shaft and the forward impel-

ling action given to the fork and its arm 47 by the action of centrifugal force, and as shown, assisted by the spring 87.

When the friction blocks 53 and 54 are moved off from the coöperating friction surfaces 50^b and 50^a, as above just described, the resistance to further inward movement of the fork toward the axis of the crank shaft 46 is immediately decreased. In Fig. 5, the dotted lines indicate the endwise contraction of the link 50—51 in which position it will be noted that the cushioning spring 57 is slightly compressed. It will, of course be understood that the momentum of 10 the fork and the outwardly pressing action of the spring 87 will be sufficient to cause reengagement of the friction surfaces 50^a and 50^b of the link member 50 with the friction blocks 52 and 53 of the link member 51.

As the loaded fork continues its rotation and approaches its uppermost position, the roller 63 of the ejector bell crank 62 will come into contact with the tripping abutment or lever 67, and thereby, operating 20 through said bell crank and the link 64 and arm 59 will impart a forward swinging movement to the ejector head or plate 58. This quick forward movement imparted to the ejector head will throw the load from 25 the teeth of the fork and impart thereto a rapid movement on a line that will approximate a line that is tangent to the line of rotation of the fork. This line of projection or discharge of the load from the fork will 30 determine the point where the load will be deposited in the wagon box, on the rack, or elsewhere, for that matter. By adjustment of the tripping abutment or lever 67, the ejector may be arranged to operate at 35 different positions of the fork, so as to throw the load from the fork either on a horizontal line or on a line diverging upwardly from a horizontal or downwardly from a horizontal, as may be desired, to effect the proper 40 discharge of the load from the fork.

The shield described, at its rear portion, is adjustable with the supporting frame 45 and crank shaft 46, but the outer portion of the shield is adjustable. Hence, by adjustments 50 of the outer end of the shield, the point at which the loads from the fork will be deposited, may be considerably varied. The adjustment of the shield should always be such that the loads thrown from the fork 55 will strike the deflecting board 99, and hence, be caused to drop properly within the wagon box, or upon the rack which is to receive the material from the forks.

In picking up manure from a large pile, 60 the machine will, from time to time, be slightly advanced and, in the loading action, the oscillating supporting frame 45 will be given different vertical adjustments to keep the fork properly in action on the pile. 65 After the machine has made one complete

trip across the pile, it should be shifted laterally closer to the pile and then be caused to make another trip across the pile until the pile has been completely picked up and loaded in wagons or on racks.

70

As already noted, simply by manipulation of the lever 33, the main driving belt 30 may be tightened or loosened at will, so as to throw the fork carrying mechanism into and out of action, as desired. It has also 75 been noted that the forward driving action of the truck may be controlled simply by manipulation of the lever 44. For driving the tractor in a reverse or backward direction it is only necessary to remove the belt 80 39, giving the same a half twist and then again apply the same to the grooved pulley 35.

The loader above described, while especially adapted for loading manure, is, nevertheless, adapted for and has been used to pick up and load various other materials, such as sand, dirt and gravel, and in such use, has also been found efficient. In the latter noted uses, the scoop is made in the 85 form of a shovel or bucket that is adapted to hold sand and such materials without leakage.

What I claim is:

1. In a loader, the combination with a 95 crank shaft and means for rotating the same, of an arm pivotally mounted on the crank of said shaft and equipped with a scoop at its outer end, an endwise contractible and extensible thrust link interposed between said crank shaft and the scoop-equipped end of said arm, the said thrust link including a spring engaged frictional detainer, the elements of which are under maximum frictional engagement when said link is extended, and which, when the link is contracted by forced inward movement of the scoop, gives away and permits further contracting movement of said link under very greatly decreased resistance.

100

2. In a loader, the combination with a crank shaft and means for rotating the same, of an arm pivotally mounted on the crank of said shaft and equipped with a scoop at its outer end, an endwise contractible and extensible thrust link interposed between said crank shaft and the scoop-equipped end of said arm, the said thrust link comprising two members, one of which is made up of a single bar with longitudinally spaced transversely widened friction surfaces, and the other member of which is made up of two laterally spaced spring bars provided with friction blocks engageable with the frictional surface of said single member, and springs for frictionally engaging the said blocks and friction surfaces when said link is extended to its limit.

115

3. In a loader, the combination with a crank shaft and means for rotating the 120 125

130

same, of an arm pivotally mounted on the crank of said shaft and equipped with a scoop at its outer end, an endwise contractible and extensible thrust link interposed between said crank shaft and the scoop-equipped end of said arm, the said thrust link including a spring engaged frictional detainer, the elements of which are under maximum frictional engagement when said link is extended, and which, when the link is contracted by forced inward movement of the scoop, gives away and permits further contracting movement of said link under very greatly decreased resistance, an ejector arm pivoted to said scoop-equipped arm and provided with an ejector head co-operating with said scoop, an ejector lever intermediately pivoted to said crank shaft and connected to said ejector arm, a spring yielding holding said ejector head and arm and lever retracted, and a trip abutment operative directly on said ejector lever and indirectly on said ejector arm to eject the load from said scoop at a predetermined point in the travel of the latter.

4. In a loader, the combination with a crank shaft and means for rotating the same, said crank shaft having a crank pin formed by an end portion thereof turned backward parallel to the body of said crank shaft, of a scoop carrying arm pivoted on said crank pin and provided with a scoop at its outer end, and means yieldingly holding said arm projected to its limit from the axis of said crank shaft.

5. In a loader, the combination with a crank shaft and means for rotating the same, said crank shaft having a crank pin formed by an end portion thereof turned backward parallel to the body of said crank shaft, of a scoop carrying arm pivoted on said crank pin and provided with a scoop at its outer end, means yieldingly holding said arm projected to its limit from the axis of

said crank shaft, an ejector carried with said scoop, and means for operating said ejector to eject the load from said scoop at a predetermined point in the travel of the latter.

6. In a loader, the combination with a crank shaft and means for rotating the same, of a scoop-carrying arm pivoted to the crank of said shaft and provided with a scoop at its outer end, means for limiting the movement of said scoop radially from the axis of said shaft, and a counter-weighted arm carried by said crank shaft and projected therefrom away from said scoop, the said counter-weighted arm being caused to rotate with said crank shaft through a spring connection that permits a limited rotary movement of one in respect to the other to thereby cushion the driving action of said weighted arm on the said scoop when the movement of the latter is interrupted, or retarded in the loading action.

7. In a loader, the combination with a crank and means for rotating the same, of an arm pivotally mounted on said crank and equipped with a scoop at its outer end, means for limiting the movement of said scoop-equipped end of said arm outward from the axis of said crank, a yielding detainer acting as an auxiliary to centrifugal force to hold said scoop at its maximum distance from the axis of said shaft, and a counter-weighted arm rotatable around the axis of said crank, projected therefrom in a direction opposite to the projection of said scoop-equipped arm and yieldingly connected to rotate with said crank.

In testimony whereof I affix my signature in presence of two witnesses.

ALBERT HOSSFELD.
